UNITED STATES PATENT OFFICE

2,520,767

EXTINGUISHER

Jay B. Hinson, Hartsdale, N. Y.

Application June 26, 1946, Serial No. 679,511

2 Claims. (Cl. 131—237)

1

This invention relates to extinguishers and is herein illustrated in some detail as embodied in an extinguisher to extinguish burning cigarettes.

In the form shown it is especially devised to be free from the tendency to clog and also in a form which is economical to build and unlikely to get out of order.

In a prior application, Serial Number 579,928, now Patent 2,406,683, I described a cigarette extinguisher which involved a funnel-shaped top into which the cigarette could be pushed against a conical head and in that device both the conical head and the funnel-shaped member were spring mounted.

That extinguisher proved effective but showed some tendency to clog because debris got into the two springs and also because the conical head might get jammed against moving.

According to the present invention those and other difficulties are overcome and a cigarette extinguisher is provided with fewer parts in which clogging is substantially impossible and yet which is adapted to be easily and cheaply assembled and the parts to be assembled can be automatically made at very low cost.

In the form shown the extinguisher is adapted to be mounted over many types of saucers so that a metal stand holding it may be readily associated with many different types of saucers for ornamental effect. The structure is also such that only the saucer need be moved for disposing of the debris.

In the form shown an outer casing is adapted to be mounted in a stamped out stand and this casing may hold a fixed conical or semi-conical extinguishing member and may include guides in which a spring supported funnel-shaped member is adapted to slide when a cigarette is inserted and guide the cigarette against the cone-shaped member.

A single spring resting on the base of the casing and bearing against the underside by a ledge of the cone-shaped member is adapted to be readily assembled and after insertion the parts are readily kept against separation by setting of a single pin in place which serves as a stop to limit the upward thrust of the spring.

Other features and advantages will hereinafter appear.

In the accompanying drawings:

Fig. 1 is a section partly diagrammatically showing the structure of the present extinguisher taken on the line 1—1 of Fig. 2;

Fig. 2 is a bottom view;

Fig. 3 shows the extinguisher in a stand holding a saucer;

2

Fig. 4 is a bottom view of the stand; and

Fig. 5 is a fragmentary view showing the extinguisher depressed in its stand.

In using the present invention, a cigarette 10 having a burning end 11 is usually thrust into the open mouth 12 of a funnel-shaped member 13 so that the body of the cigarette on reaching the constriction 14 carries down the funnel-shaped member 13 against the tension of the spring 15.

As the funnel-shaped member 13 goes down the lighted end 11 of the cigarette strikes the cone-like member 16 which projects upwardly and is preferably formed of solid metal so that the cooling effect of the solid body extinguishes the burning end 11 and effectively puts out all sparks in it.

The cigarette is then withdrawn and dropped into a saucer or other receptacle 17 which is shown resting on the stand 18 which carries the extinguisher casing 19.

In the form shown the cone-shaped member 16 is carried on a cross-bar 20 forming the bottom of the casing 19 so that the cone-shaped member 16 rises within the depending walls 21 which form an extension of the funnel-shaped member 13.

In the form shown the walls 21 are slotted at 22 so as to ride on opposite sides of notches or depressions 23 cut in the cross-bar 20. Thus the cross-bar 20 forms a guide for the bottom of the funnel-shaped member 13 as it descends. The walls 21 form hoods which keep the ashes and other debris away from the spring 15 which lies between the walls 21 and the vertical outer wall 24 of the casing 19.

In the form shown the ends of the spring 15 lie flat on the opposite ends of the cross-bar 20 and on the bottom overhanging ledge 25 of the casing.

The thick walls 26 which form the body of the funnel-shaped member 13 help to absorb the heat of the burning cigarette and normally extend a small fraction of an inch down within the walls 24 of the casing.

The casing is shown as provided with an annular projecting rim 27 which is adapted to rest upon the top 28 of an annular ring 29 which forms the upward terminus of an arm 30 of the supporting stand 18.

In the form shown the stand 18 is provided with wide spreading flat arms 31 so that it tends to rest solidly on the table or other support. The upwardly extending arm 32 is usually bent so that the ring 29 lies about above the center line between the ends 33 of the wings 31.

In order to assemble the extinguisher easily and rapidly the slots 22 are shown as open at their bottom and the upward thrust of the funnel-shaped member 13 by the spring 15 is shown as limited by a pin 34 projecting from one of the walls 24 and adapted to be arrested in an opening or notch 35 on the bottom edge of a wall 24. Thus the pin 34 may allow the walls 21 to rise until they disappear or nearly disappear within the walls 24.

For convenience in building, the cone-shaped member 16 is shown as a separate solid member having an annular ledge 37 near its bottom and a reduced extension 38 which is adapted to pass through the cross-bar 20 and be riveted or welded into the bottom of the cross-bar 20.

The cone-shaped member 16 is shown with a slight flare 40 at the bottom of its surface, and this flare closes the opening between it and the bottom of the funnel when the funnel is pressed. The walls 26 are slightly bulged at 41 so that when the funnel is thus pressed down it is held down by friction of the bulges 41 on the inside of the walls. This enables the extinguisher to completely close, serving to close a box if mounted on a box cover instead of the stand 18.

Having thus described certain embodiments of the invention, what is claimed is:

1. In a cigarette extinguisher a casing, a funnel-shaped cigarette receiving member slidably in the casing, a cone-shaped extinguishing unit toward which the member carries the cigarette, a spring yieldably supporting the member, and a

fixed cross-bar at the bottom of the casing to which the cone-shaped unit is fixed and supporting the spring, said member provided with skirts forming protecting walls within said casing and protecting the spring throughout its length.

2. In a cigarette extinguisher a hollow casing having a bottom cross-bar, a funnel-shaped cigarette receiving member slidable in the casing, a solid metal cone-shaped extinguishing unit fixed to the cross-bar and rising from the cross-bar into the member, and a spring on the cross-bar normally holding the member with its funnel above the cone, said funnel-shaped member provided with skirts keeping debris from the spring throughout its length, said cross-bar provided with slots to provide a guide-way for said skirts.
